[57] CLAIM

The ornamental design for a guide for power tools, as shown and described.

DESCRIPTION

FIG. 1 is a side elevational view of the guide for power tools showing our new design;

FIG. 2 is an opposite side elevational view thereof; FIG. 3 is a top plan view thereof, the bottom being plain and unornamented;

FIG. 4 is an enlarged fragmentary cross-sectional view of the guide rail thereof, taken along line 4—4 on FIG. 3;

FIG. 5 is an end elevational view thereof; and

FIG. 6 is an opposite end elevational view thereof.

FIG. 1

FIG. 2

FIG. 3

FIG. 4

FIG. 5

FIG. 6
